(57) **ABSTRACT**

A padding assembly for a helmet includes a plurality of pads that is configured to couple to an external surface of the helmet, such as a football helmet. The pads are configured to absorb a force from an impact to the helmet when the helmet is positioned on a head of a user. The force of the impact to the head of the user is reduced.

BACKGROUND OF THE INVENTION

(1) Field of the Invention

(2) Description of Related Art Including
Information Disclosed Under 37 CFR 1.97 and
1.98

The disclosure and prior art relates to padding assemblies and more particularly pertains to a new padding assembly for a helmet.

BRIEF SUMMARY OF THE INVENTION

An embodiment of the disclosure meets the needs presented above by generally comprising a plurality of pads that is configured to couple to an external surface of a helmet, such as a football helmet. The pads are configured to absorb a force from an impact to the helmet when the helmet is positioned on a head of a user. The force of the impact to the head of the user is reduced.

There has thus been outlined, rather broadly, the more important features of the disclosure in order that the detailed description thereof that follows may be better understood, and in order that the present contribution to the art may be better appreciated. There are additional features of the disclosure that will be described hereinafter and which will form the subject matter of the claims appended hereto.

The objects of the disclosure, along with the various features of novelty which characterize the disclosure, are pointed out with particularity in the claims annexed to and forming a part of this disclosure.

**BRIEF DESCRIPTION OF SEVERAL VIEWS OF
THE DRAWING(S)**

The disclosure will be better understood and objects other than those set forth above will become apparent when

2

consideration is given to the following detailed description thereof. Such description makes reference to the annexed drawings wherein:

FIG. 1 is an isometric perspective view of a padding assembly according to an embodiment of the disclosure.

FIG. 2 is a back view of an embodiment of the disclosure.

FIG. 3 is a front view of an embodiment of the disclosure.

FIG. 4 is a top view of an embodiment of the disclosure.

FIG. 5 is a side view of an embodiment of the disclosure.

FIG. 6 is an in-use view of an embodiment of the disclosure.

FIG. 7 is an isometric perspective view of an embodiment of the disclosure.

FIG. 8 is a side view of an embodiment of the disclosure.

15

**DETAILED DESCRIPTION OF THE
INVENTION**

With reference now to the drawings, and in particular to FIGS. 1 through 8 thereof, a new padding assembly embodying the principles and concepts of an embodiment of the disclosure and generally designated by the reference numeral 10 will be described.

As best illustrated in FIGS. 1 through 8, the padding assembly 10 generally comprises a plurality of pads 12 that is configured to couple to an external surface of a helmet, such as a football helmet. The pads 12 are configured to absorb a force from an impact to the helmet when the helmet is positioned on a head of a user. The force of the impact to the head of the user is reduced. In one embodiment, the plurality of pads 12 comprises one pad 12 configured to cover substantially all of the external surface of the helmet.

In one embodiment, the pads 12 comprise foam. In another embodiment, the pads 12 comprise pliable foam. In yet another embodiment, the pads 12 are circularly shaped. In still yet another embodiment, the plurality of pads 12 comprises a first absorber 14 that is centrally positioned above and adjacent to the front opening of the helmet. This embodiment also comprises a pair of second absorbers 16 and two pairs of third absorbers 18. The second absorbers 16 extend from the first absorber 14 linearly along a centerline of the helmet to a back of the helmet. Each pair of third absorbers 18 is positioned between the first absorber 14 and a point above a respective earhole of the helmet. In still yet another embodiment, each pad 12 is selectively contoured so that the pad 12 resembles an object, such as a paw.

A plurality of first couplers 20 is coupled to the helmet. Each of a plurality of second couplers 22 is coupled to a respective pad 12. The second couplers 22 are complementary to the first couplers 20. The second couplers 22 are positioned on the pads 12 such that each second coupler 22 is positioned to couple to a respective first coupler 20 to couple the pad 12 to the helmet. In one embodiment, each second coupler 22 and the respective first coupler 20 comprise a snap connector 24. In another embodiment of the invention, the plurality of pads 12 is integral to the helmet.

In use, the second couplers 22 are positioned on the pads 12 such that each second coupler 22 is positioned to couple to the respective first coupler 20 to couple the pad 12 to the helmet. The pads 12 are positioned on the helmet so that the pads 12 are configured to absorb the force from the impact to the helmet when the helmet is positioned on the head of the user. The force of the impact to the head of the user is reduced.

65 With respect to the above description then, it is to be realized that the optimum dimensional relationships for the parts of an embodiment enabled by the disclosure, to include

variations in size, materials, shape, form, function and manner of operation, assembly and use, are deemed readily apparent and obvious to one skilled in the art, and all equivalent relationships to those illustrated in the drawings and described in the specification are intended to be encompassed by an embodiment of the disclosure.

Therefore, the foregoing is considered as illustrative only of the principles of the disclosure. Further, since numerous modifications and changes will readily occur to those skilled in the art, it is not desired to limit the disclosure to the exact construction and operation shown and described, and accordingly, all suitable modifications and equivalents may be resorted to, falling within the scope of the disclosure. In this patent document, the word "comprising" is used in its non-limiting sense to mean that items following the word are included, but items not specifically mentioned are not excluded. A reference to an element by the indefinite article "a" does not exclude the possibility that more than one of the element is present, unless the context clearly requires that there be only one of the elements.

I claim:

1. A padding assembly comprising:
a plurality of pads configured for coupling to an external surface of a helmet, wherein said pads are positioned on the helmet such that said pads are configured for absorbing a force from an impact to the helmet when the helmet is positioned on a head of a user such that the force of the impact to the head of the user is reduced, said plurality of pads comprising a first absorber centrally positioned above and adjacent to the front opening of the helmet; 30
a pair of second absorbers extending from said first absorber linearly along a centerline of the helmet to a back of the helmet; and
two pairs of third absorbers, each said pair of third absorbers being positioned between said first absorber and a point above a respective earhole of the helmet spaced apart and such that each of said third absorbers is fully positioned vertically above a line extending between a top of the front opening and a top of the earhole. 35
2. The assembly of claim 1, further including said pads comprising foam.
3. The assembly of claim 2, further including said pads comprising pliable foam. 45
4. The assembly of claim 1, further including said pads being circularly shaped.
5. The assembly of claim 1, further including said pads being selectively contoured such that each pad resembles a paw. 50
6. The assembly of claim 1, further comprising:
a plurality of first couplers coupled to the helmet; a plurality of second couplers, each said second coupler being coupled to a respective said pad, said second couplers being complementary to said first couplers; and 55

wherein said second couplers are positioned on said pads such that each said second coupler is positioned for coupling to a respective said first coupler to couple said pad to the helmet.

- 5 7. The assembly of claim 6, further including each said second coupler and said respective said first coupler comprising a snap connector.
8. The assembly of claim 1, further including said plurality of pads being integral to the helmet.

9. A padding assembly comprising:
a plurality of pads configured for coupling to an external surface of a helmet, wherein said pads are positioned on the helmet such that said pads are configured for absorbing a force from an impact to the helmet when the helmet is positioned on a head of a user such that the force of the impact to the head of the user is reduced, said pads comprising foam, said pads comprising pliable foam, said pads being circularly shaped, said plurality of pads comprising a first absorber centrally positioned above and adjacent to the front opening of the helmet, a pair of second absorbers extending from said first absorber linearly along a centerline of the helmet to a back of the helmet, and two pairs of third absorbers, each said pair of third absorbers being positioned between said first absorber and a point above a respective earhole of the helmet spaced apart and such that each of said third absorbers is fully positioned vertically above a line extending between a top of the front opening and a top of the earhole;

a plurality of first couplers coupled to the helmet; a plurality of second couplers, each said second coupler being coupled to a respective said pad, said second couplers being complementary to said first couplers, wherein said second couplers are positioned on said pads such that each said second coupler is positioned for coupling to a respective said first coupler to couple said pad to the helmet, each said second coupler and said respective said first coupler comprising a snap connector; and

wherein said second couplers are positioned on said pads such that each said second coupler is positioned for coupling to said respective said first coupler to couple said pad to the helmet, wherein said pads are positioned on the helmet such that said pads are configured for absorbing the force from the impact to the helmet when the helmet is positioned on the head of the user such that the force of the impact to the head of the user is reduced.

- 50 10. The assembly of claim 9, further including said plurality of pads being integral to the helmet.
11. The assembly of claim 9, further including said pads being selectively contoured such that each pad resembles a paw.
